METAL RECEPTACLE

Louis M. Piker, Hamilton, Ohio, assignor to The
Hamilton Metal Products Company, Hamilton,
Ohio, a corporation of Ohio

Application April 29, 1935, Serial No. 18,836

12 Claims. (Cl. 220—62)

This invention relates to improvements in metal receptacles particularly of the box type which are formed from a single sheet of steel or the like and the invention relates specifically to the corner construction of such receptacles.

More specifically this invention relates to improvements in the receptacles such as shown in the Louis M. Piker patent, No. 1,912,915, issued June 6, 1933. This patent is directed to the improved corner construction of said receptacles where the sides and ends meet thereby providing a construction in which the said corners are rounded. By the present invention the said receptacles are not only provided with rounded corners where the sides and ends meet but also with rounded corners where the top and sides or ends meet as well as at the point where all three of these parts connect. It is, therefore, one of the chief objects of the present invention to provide a receptacle having all of its corners rounded instead of some of them round and some sharp.

Another object of this invention is the provision of an improved blank from which a receptacle as above noted may be formed.

Another object of the invention is the provision of a metal container or receptacle having secured thereto extraneous corner pieces whereby a smooth rounded surface is provided at the point of juncture of the side, end and top of the receptacle which corner would be deformed if attempted to be drawn or bent to this shape.

Other objects and advantages of the present invention should be readily apparent by reference to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings.

Fig. 1 is a top plan view of a container or receptacle embodying the improvements of this invention;

Fig. 2 is a front elevation of Fig. 1;

Fig. 3 is an end elevation of Fig. 1;

Fig. 4 is an enlarged fragmentary sectional view as seen from line 4—4 on Fig. 2 and illustrating the corner of the container;

Fig. 5 is a fragmentary horizontal sectional view to the same scale as Fig. 4 and as seen from line 5—5 on Fig. 2;

Fig. 6 is a fragmentary sectional view similar

to Fig. 5 but taken on a plane below Fig. 5 as seen from line 6—6 on Fig. 4;

Fig. 7 is a perspective view of the corner piece utilized to complete and provide a smooth rounded corner at the point of juncture of the end, side and top;

Fig. 8 is a plan view of a blank from which the improved receptacle of this invention is formed, said blank in Fig. 8 showing the interior of the final receptacle;

Fig. 9 is a staggered sectional view through the extended blank as seen from line 9—9 on Fig. 8;

Fig. 10 is a fragmentary sectional view similar to Fig. 4 but illustrating a modification in the mounting of the corner pieces;

Fig. 11 is a fragmentary sectional view similar to Fig. 10 illustrating a further modification of the mounting of the corner pieces.

Throughout the several views of the drawings similar reference characters are employed to denote the same or similar parts.

As was noted above this invention pertains to improvements on the prior patent to this inventor and is specifically directed to a structure in which remaining corners of the receptacle are rounded, which are the corners where the sides and ends join with the top or bottom as well as the corner where these three parts meet. As will be seen from the drawings the invention is particularly applicable to the lid or cover of the receptacle rather than the bottom where it may be desirous of having a sharp or right angle corner.

The receptacle as shown in the drawings comprises a bottom section or box 15 and a top section or lid 16 which are hinged to one another along the rear side 17 of Fig. 1. The bottom 15 may be constructed as disclosed in the above mentioned prior patent of Louis M. Piker No. 1,912,915 except in one particular which will be pointed out later. The top or cover 16 is formed from the blank illustrated in Fig. 8 which will now be described in detail.

The blank of Fig. 8 has a central or body portion 18 which constitutes the top surface of the receptacle cover or lid which is provided with a raised portion bounded by the lines 19, 20, 21 and 22. Integral with the body portion 18 are the end portions 23 and 24 and side portions 25 and 26. Each of the end portions 23 and 24 is provided with a pair of embossed decorative and strengthening ribs 27 and 28 as well as a lip portion 29 which is adapted to be folded onto the side 23 along the broken line 30 and thereby provide a re-enforced edge for the said ends. The front side 26 of the blank is provided with a pair

of decorative and strengthening ribs 31 and 32 which extend throughout the length thereof. The said side 26 is additionally provided at its free edge with a lip 33 of a length less than the 5 length of the said side which is to be bent onto the side along the broken line 34 to strengthen the edge of the receptacle. The remaining or back side 25 of the blank is also provided with a pair of decorative and strengthening ribs 35 and 10 36. The free edge of the side 25 is provided with three lips or tabs 37, 38 and 39 of which tabs 37 and 39 are adapted to be bent onto the side 25 along the broken lines 40 and 41 for strengthening the edge of the receptacle while the lip 38 is 15 to be formed into a hinge eye as shown in dotted lines at 42 in Fig. 9.

The body portion 18 is provided centrally thereof with a plurality of apertures 43 for attaching to the receptacle the lugs 44 and 45, see 20 Fig. 1, which in turn have hingedly connected therewith the bail handle 46. The front side 26 is likewise provided with a plurality of apertures 47 which receive the lugs or fastening means of a lock or other suitable clasp for securing the 25 lid or cover to the section or box in closed position.

The receptacle is made by first piercing or stamping a flat sheet substantially to the outline as shown in Fig. 8, but without the decorative 30 and strengthening ribs, embossed upper surface or other bends, to be later described, therein. This blank is provided at ends of the front and back sides 25 and 26, at the points where the strengthening and decorative ribs are to be 35 stamped, with lugs or teats shown in Fig. 8 in dotted lines at 48. These lugs or teats 48 are so proportioned that during the stamping or embossing operation they are drawn toward the center of the sides so that the edge is in the same 40 plane throughout the height thereof, that is, the edge of the sides and the embossed ribs lie in the same vertical plane when the pan is bent to proper position. It is in this particular that the bottom section or box 15 differs from that shown in the 45 prior patent, above referred to; in other words, the blank shown in the prior patent would be provided with lugs or teats, such as 48, at the points of the decorative and strengthening ribs so that the edges of the sides and ribs would be 50 in the same plane instead of having the edges of these ribs arcuately receding from said plane.

After the sheet has been stamped, pierced and embossed it is folded to the proper form which as shown in Figs. 2 and 3 is rectangular in shape. 55 By this folding the portion of the blank between the body portion 18 and the lowermost decorative and strengthening rib of the sides and ends is rounded. It will be appreciated that this would tend to stretch the metal at the corners of the 60 body portion 18 where the sides and ends are joined to one another in several directions resulting in a corner having an undulated or corrugated and unsightly appearance. To avoid this the material at these corners is entirely removed as shown at 48' in Fig. 8. The opening formed by the removal of this metal is bounded by a line 49 extending parallel with the free edge of the sides which line is tangent to an arcuate edge 50. The arcuate edge 50 in turn connects 65 with an arcuate edge 51 which in reality is the edge of the flat top surface of cover or lid and from which the rounded corner extends. Connected with the other end of the arcuate edge 51 is a third arcuate edge 52 which is similar to the 70 arcuate edge 50 and has extending tangentially

therefrom the edge 53 which is angularly related to the free edge of the end sections.

When the sides and ends are folded to their operative positions the boundaries of the opening 48' form an elongated aperture at the corner 5 point where the metal would be stretched in the different directions, as above mentioned, this opening being shown at 54 in Figs. 4 and 5. It should be noted at this time, and as above mentioned, that the boundary 51 is substantially at 10 the beginning of the round of the top toward the side and end while the straight edge 49 is substantially at the bottom of this round or where it joins with the vertical surfaces of the side and end. With the parts in this position the adjacent edges of the side and ends overlap one 15 another and in order to provide a smooth outer surface the lateral sides of the ends 23 and 24 are each respectively depressed up to the lines 55 and 56 for a depth equal to the gauge or thickness 20 of the metal and it is into this depression that the adjacent edge of the adjacent front or back is seated.

In order to continue the smooth surface at the 25 point of jointure of the side, end and top the said parts are depressed around the aperture 54 which depression is bounded by the adjacent strengthening or decorative ribs of said side and end, the lines 57 and 58 and the corner 63 of the top 30 raised portion and it is into this depression that the corner pieces 59, see Fig. 7, are fitted. From this it will be seen that the ends 23 and 24 have a portion which is depressed to a double depth and this portion is bounded by the edge 53 of the opening, free lateral edge, adjacent rib 27, and 35 line 55 between said adjacent rib and the opening edge 53. It should also be noted that the decorative and strengthening ribs 27 and 28, of the sides 23 and 24, from the depression lines 55 and 56 to the lateral free edges thereof, are of less width 40 than between said lines since it is necessary that the said rib portions fit within the rib portions of the front and back sides.

One of the corner pieces 59 is shown in perspective in Fig. 7 and comprises a triangular body portion 60 having its corner removed as at 61 and from which body portion extends a skirt 62. Said skirt 62 is semi-circular to conform with the rounded corner at the point where the sides and ends connect with one another and at the same time the body portion 60 and skirt 59 are 50 connected to one another by an arcuate fillet which corresponds to the rounded corner existing at the point of connection of the top with the sides and ends. The cut away portion 61 of the body portion corresponds with the corner 63 of the 55 embossed top surface.

After the parts have been bent to the proper position and shape they are secured to one another by any suitable or desirable means such as 60 sweating, soldering, or spot welding, the latter being shown in the drawings and indicated by the reference character 64. From the foregoing it will be noted that there has been provided a receptacle in which all of the corners are not 65 only given a rounded form but with the corners at the point of juncture of the ends, sides and top substantially re-enforced to withstand blows occasioned by dropping or shifting the said receptacle.

Instead of securing the corner pieces as above noted the same may be held in operative position by means of spring clips or arms which project from the under surface of said corner pieces and are inserted through the aperture 54. This 70 75

construction is shown in Fig. 10 and comprises arms or lugs 68 and 69 respectively engaging the inner surface of the side 24 and front 26. These arms 68 and 69 instead of being in the nature of spring clips may be fastening members pressed to position by a suitable die or clamping block to closely engage the above mentioned portions of the receptacle.

By this construction the said corner pieces may be nickel-plated or enameled so as to contrast with the color or finish of the remaining part of the receptacle, while if the said corner pieces were spot welded in position this would either damage the finish on said corner pieces or result in a tedious finishing job.

As shown by Fig. 11, the said corner pieces instead of being mounted on the exterior of the receptacle may be secured in position on the interior thereof with the body portion of said corner piece, indicated in Fig. 11 by the reference character 70, forced outwardly so that its outer surface is substantially in the same plane as the surfaces of the sides, ends and top of the receptacle.

In each of these constructions it will be noted that there has been provided an extraneous corner or cover for the apertures at the corners of the receptacle and that these covers or corner pieces may be finished the same as the body portion of the receptacle or finished to contrast therewith for ornamental or decorative purposes.

What is claimed is:

1. A metal receptacle of the class described comprising a base and walls extending therefrom at an angle thereto, said receptacle having rounded corners at the point where the walls are connected with the base, said walls overlapping one another at their adjacent ends to provide rounded corners at the points where the walls connect with one another and having at the points of juncture of said walls with said base an elongated aperture, and a cover for said aperture comprising a flat portion adapted to rest on the base and a semi-circular skirt resting against the walls of the receptacle and completing the walls and base surfaces with a rounded corner at their points of juncture.

2. In a metal receptacle of the class described the combination of a base having extending therefrom side and end walls, the adjacent ends of the side and end walls overlapping one another, said receptacle having apertures at the points of juncture of the side and end walls and the base, and a cover for each aperture comprising a flat portion adapted to rest on the base and a semi-circular skirt resting against the walls of the receptacle for closing said apertures.

3. In a receptacle of the class described the combination of a base having extending from the edges thereof wall members disposed at an angle to the base, said wall members overlapping one another at their corners, said wall members and base each having material removed therefrom at and around their points of juncture with one another whereby an aperture is formed at each of these points, and a corner piece comprising a flat portion adapted to rest on the base and a semi-circular skirt resting against the walls of the receptacle adapted to close each of said apertures and conforming in general with the adjacent walls and base of the container.

4. A container of the class described having a base and side walls with formed rounded corners at their contiguous portions, said receptacle having an offset depression in the material at

said corners and a corner piece in each of said depressions at the points of common engagement of the walls and base.

5. In a metal receptacle of the class described, the combination of a base, walls extending from the base at an angle thereto, rounded corners at the point of juncture of the walls with the base, rounded corners at the point of juncture of the walls with one another, an aperture at the point of connection of the base with the walls, an offset in the material around the aperture, and a cover for said aperture, disposed in said offset space, whereby the outer walls, base and corner surfaces are flush.

6. In a metal container of the class described, the combination of a rectangular base, side and end walls projecting from the base at an angle thereto, the adjacent ends of the side and end walls overlapping one another to provide a continuous wall for the receptacle, said receptacle having an aperture at each corner thereof where the adjacent ends of the side and end walls and base of the receptacle meet, the material of the receptacle around each aperture being offset a distance equal to the gauge of a cover for the apertures, and a formed cover disposed in the offset portion around each aperture for closing same and continuing the rounded corners of connection of the walls with one another and with the base.

7. In a metal container of the class described, the combination of a rectangular base, side and end walls projecting from the base at an angle thereto, the adjacent ends of the side and end walls overlapping one another to provide a continuous wall for the receptacle, said receptacle having an aperture at each corner thereof where the adjacent ends of the side and end walls and base of the receptacle meet, the material of the receptacle around each aperture being offset a distance equal to the gauge of a cover for the apertures, a formed cover disposed in the offset portion around each aperture for closing same and continuing the rounded corners of connection of the walls with one another and with the base, and means for securing the cover piece in position.

8. In a metal container of the class described, the combination of a rectangular base, side and end walls projecting from the base at an angle thereto, the adjacent ends of the side and end walls overlapping one another to provide a continuous wall for the receptacle, said receptacle having an aperture at each corner thereof where the adjacent ends of the side and end walls and base of the receptacle meet, the material of the receptacle around each aperture being offset a distance equal to the gauge of a cover for the apertures, a formed cover disposed in the offset portion around each aperture for closing same and continuing the rounded corners of connection of the walls with one another and with the base, means for securing the cover piece in position, comprising spot welding of the cover piece to the depressed material around the aperture.

9. In a metal container of the class described, the combination of a rectangular base, side and end walls projecting from the base at an angle thereto, the adjacent ends of the side and end walls overlapping one another to provide a continuous wall for the receptacle, said receptacle having an aperture at each corner thereof where the adjacent ends of the side and end walls and base of the receptacle meet, the material of the receptacle around each aperture being offset a

distance equal to the gauge of a cover for the apertures, a formed cover disposed in the offset portion around each aperture for closing same and continuing the rounded corners of connection of the walls with one another and with the base, and means for securing the cover piece in position, comprising arms secured to the inner surface of the cover piece and projecting through the aperture into engagement with the inner surface of the receptacle adjacent the aperture.

10. A cover for the aperture left in a drawn and formed metal receptacle that has a rounded corner at the point where the base or top of said receptacle meets the integral side walls, comprising a flat base portion for the cover and an arcuate skirt portion extending therefrom and connected with one another by a rounded fillet, said cover base portion and skirt portion together covering a greater area than the area of the aperture, and means carried by the cover and projecting through the aperture for securing the cover in position.

11. In a metal receptacle of the class described, the combination of a base, side and end walls projecting from the base at an angle thereto, the adjacent end of the side and end walls overlapping one another to provide a continuous wall for the receptacle, said receptacle having an aperture at each corner thereof where the adjacent

corners of the side and end walls and base meet, a formed metal cover disposed over each aperture and closing same and continuing the rounded corner of connection of the walls with one another and with the base, and means for securing the cover pieces in position, comprising arms secured to the inner surface of each cover piece and projecting through the aperture into engagement with the inner surface of the receptacle adjacent the aperture.

12. In a metal receptacle of the class described, the combination of a base, side and end walls projecting from the base at an angle thereto, the adjacent ends of the side and end walls overlapping one another to provide a continuous wall for the receptacle, said receptacle having an aperture at each corner thereof where the adjacent corners of the side and end walls and base meet, and a formed metal cover disposed interiorly of the receptacle at the corners thereof, said cover having a portion offset an amount equal to the thickness of the metal around the apertures and with said offset portion projecting through the apertures for closing the same, and said covers having portions thereof adjacent the apertures respectively secured to the end and side walls and the base.

LOUIS M. PIKER.
